(57) **CLAIM**

An ornamental design for a catheter actuation handle, as shown and described.

DESCRIPTION

FIG. 1 is a side view of the left-side of a catheter actuation handle in combination with an unclaimed articulable distally-extending member, in accordance with the present invention; a right-side view of the catheter actuation handle is the same in appearance as the left-side view of FIG. 1. FIG. 2 is a top view of the catheter actuation handle of FIG. 1; a bottom-side view of the catheter actuation handle is the same in appearance as the top-side view of FIG. 2. FIG. 3 is a proximal-end view of the unclaimed proximal end features of the catheter actuation handle of FIG. 1. FIG. 4 is a distal-end view of the catheter actuation handle of FIG. 1; and, FIG. 5 is a perspective view of the catheter actuation handle of FIG. 1 shown with an unclaimed Y-connector structure extending from the proximal end shown in FIG. 3. The broken lines in the drawing depict environmental subject matter only and form no part of the claimed design.
